UNITED STATES PATENT OFFICE.

AUGUSTE JOSEPH FRANÇOIS DE BAVAY, OF KEW, VICTORIA, AUSTRALIA.

APPARATUS FOR SEPARATING ORES BY FLOTATION

No. 912,783.

Specification of Letters Patent.

Patented Feb. 16, 1909.

Application filed December 19, 1904. Serial No. 237,585.

To all whom it may concern:

Be it known that I, AUGUSTE JOSEPH FRANÇOIS DE BAVAY, a subject of the King of Great Britain and Ireland, residing at "Florimel," Gellibrand street, Kew, in the British State of Victoria, Commonwealth of Australia, brewer and chemist, have invented a certain new and useful Apparatus for Separating Ores by Flotation, of which the following is a specification.

This invention consists of an apparatus for separating by flotation parts of the constituents of ores, gangues, tailings, concentrates, slimes and other solid bodies such as earths or rock containing particles capable of flotation which it is desired to separate from the remainder thereof. The term "water" is hereinafter used to mean and include water or other liquid on which the particles which it is desired to separate are capable of flotation. The ore (which term is hereinafter used to mean and include all such bodies) to be treated or the solid particles thereof, must be in a suitably pulverized condition and saturated with water. I have found in practice that a degree of division enabling the particles of the ore to pass through a 40 mesh sieve and not to pass through a 100 mesh sieve is suitable.

The invention will now be described aided by a reference to the accompanying sheets of drawings which illustrates an apparatus built according to my invention and in which:

Figure 1 is a sectional side view of an apparatus constructed according to my invention; Fig. 2 is a front view of the same; Fig. 3 is a broken sectional view of a portion of a trough, showing the application of the adjustable lip thereto; and Fig. 4 is a broken detail view of said lip.

The apparatus consists in the first place of an inclined surface or table A suitably erected, supported and constructed so that it can be adjusted at an angle to the horizontal or if fixed, supported at an angle of about 45° thereto somewhat as shown and preferably made of or covered with metal or other non-absorbent material and if desired divided by division ribs as α (shown by dotted lines in Fig. 2) into a series of races. At the upper end of the apparatus is a feed pipe B having perforations b along its lower side and having a rotary worm B' therein, or the feed device may be in the form of a feed hopper or bin provided with an ad-

justable delivery nozzle or nozzles or other feed device. From said perforated pipe B the ore in a pulverized condition and saturated with water is fed in a regulated quantity supplied from a cistern as C on to the inclined surface or table A in a thin paste.

D is a pipe fed from any convenient source and provided with nozzles d for supplying a small stream of water sufficient to carry the ore down the inclined surface or table in a thin film such being aided by transverse brushes or distributors E. The lower part of such inclined surface or table A dips into or terminates in a shallow trough, or well F hereinafter termed a trough which when the apparatus is in use is filled with water to the level of an overflow lip or ledge F' arranged at the side or part of trough in front of the inclined table or surface and outside of said ledge is a gutter G leading away at a downward inclination from such trough to a suitable bin the upper end of said gutter being slightly below the level of the ledge of trough F to provide an overflow therefrom, while said ledge or lip F' is made in the form of a sliding plate secured by thumb screws f to be adjustable in order that the height of water in the trough may be regulated to a small extent. In the said trough F under the lower end of the inclined table A the front part of an endless traveling belt or table H is arranged which table is carried on rollers h in such a manner as to have two inclined planes one leading from under the water at front of trough to over its back edge and the other plane leading down therefrom to deliver the materials aided by a stream or spray of water from a pipe H' to the inclined table A of another apparatus of the same kind the construction being repeated as often as may be necessary or desirable and erected so that the whole will work continuously when once started. If so desired said endless traveling belt may be provided with transverse slats or ribs or the like, and further the belt may be carried on endless chains supported on sprocket wheels or chain sheaves. In Fig. 1 the traveling belts H are connected by a crossed belt h^1 on pulleys h^2 on two of the roller spindles to one of which pulleys motion is imparted.

If continuous action is desired the before-mentioned cisterns C should be arranged in pairs as shown in Fig. 2 each provided with stirrers or agitators C' carried on a central

vertical spindle C² to which rotary motion is imparted. They are also furnished with man hole or feed doors C³.

The supply of the ore from the cisterns c 5 to the pipe B is controlled by suitable valves, and in order to thoroughly agitate the ore in said cisterns each may be provided near its lower end with an inlet C⁵ and at its top with an outlet C⁶ through which compressed

10 air or other gaseous medium may enter and escape. The outlet C⁶ of one cistern is connected through a suitable pipe or conduit with the inlet C⁵ of an adjacent cistern, the object being that at intervals the valves con-

15 trolling the supply of ore from the cisterns to the pipe B may be closed and compressed air or other suitable gaseous medium admitted through the inlet C⁵ of one of the cisterns, pass up through the ore in said

20 cistern to thoroughly agitate it, and pass out through the outlet C⁶ at the top and thence to the inlet C⁵ of the adjacent cistern.

Each of the cisterns is further provided with a pressure gage to indicate the pressure 25 of the compressed air or gas therein.

Water is admitted to each cistern, near the bottom thereof, through an inlet C⁷ and permitted to escape through an outlet C⁸ near the top.

30 The transverse brushes or distributors E work at one end in guides E¹, while their other ends are carried by the pivoted levers E² the outer arm of each being attached by a rod E³ to an eccentric E⁴ on one of the rotary shafts of apparatus.

In order to effect the separation required 40 an ore which either with or without washing, sifting or preliminary chemical treatment possesses particles capable of flotation which it is desired to separate, and which

washing and chemical treatment may be done in the cisterns C, is fed from the said cisterns into the perforated pipe B and from thence on to the said inclined surface or

45 table A in a thin pasty condition and is then carried down by a small stream of water from the said pipe D in a thin film, which is evenly distributed by the transverse brushes E, to the surface of the water in the

50 said trough F in the manner and direction favorable to the flotation of such particles thereof as are capable of flotation, and which it is desired to separate, notwithstanding that many or all of such particles

55 may be of greater specific gravity than the water or other liquid. Most of such particles are carried along the surface of the water in the trough F into the gutter G leading away therefrom and thence into a

60 bin at the end thereof to be dealt with as may be desired. The residue or remainder

of the particles sinks in the water in the said trough F to upon the said endless traveling belt H, which carries it upwards and over the back edge of trough and delivers it 65 aided by a stream of water from pipe H¹ to another inclined table A at a lower level and so on till the required separation is effected when the ultimate remainder may be dealt with as may be desired.

The length and inclination of the surface or table, the quantity of water used to form the stream and the height of the said adjustable lip, or ledge, should be regulated so as to bring about a speed and direction 70 necessary to deliver a thin film of the ore onto the surface of the water in the trough and to carry a thin film of the particles capable of flotation which it is desired to separate along such surface and the dimensions and adjustment of the endless traveling belt or table and the breadth of the trough should be sufficient to enable all or nearly all the particles not capable of flotation or which it is not desired to separate 75 to sink, and be delivered to the next inclined surface or table. The ascertainment of these matters can be easily made by a few trials having regard to the ore under treatment and the liquid or liquids used and 80 where desirable adjustments can be made in some of them without altering the others.

Having now described my invention, what I claim as new and desire to secure by Letters Patent is:—

In an apparatus of the class described, the combination of a feed pipe, a rotary worm therein, an ore supply connected to each terminal of said pipe, a water supply pipe arranged parallel and adjacent to said feed pipe, a plurality of inclined chutes, distributing means extending transversely of each chute, a liquid containing receptacle at the lower end of each chute, provided at one side with an adjustable overflow lip 100 and inclined gutter for receiving and conveying the particles capable of flotation, an endless traveling belt in each of said receptacles having one end submerged therein and adapted to convey the heavier constituents from one trough to the succeeding inclined chute, spray pipes adapted to deliver water upon the belts after they have emerged from said receptacles, and operating means common to said distributing 110 and said endless traveling belts.

In witness whereof I have hereunto set my hand in presence of two witnesses.

AUGUSTE JOSEPH FRANCOIS DE BAVAY.
